CLAIM

The ornamental design for portion of a microphone wand, as shown and described.

DESCRIPTION

FIG. 1 is a perspective view of a portion of a microphone wand showing my new design, the broken line showing of the ceiling is for illustrative purpose only, and forms no part of the claimed design;

FIG. 2 is a top plan view thereof;

FIG. 3 is a front elevational view thereof, the rear view being identical;

FIG. 4 is a bottom plan view thereof; and,

FIG. 5 is an enlarged right side elevational view thereof.
